(57) **CLAIM**

The ornamental design for a fender, as shown and described.

DESCRIPTION

FIG. 1 is a front, right side, top perspective view of a fender showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

A second embodiment of the claimed design for the fender is a mirror image of the fender as shown in FIGS. 1 to 7. The broken lines in the drawings indicate a boundary between claimed and unclaimed portions, and form no part of the claimed design. The deemphasized, grayscale portions shown inside the broken line boundary form no part of the claimed design.
